CLAIM

The ornamental design for a portable toilet, as shown and described.

DESCRIPTION

FIG. 1 is a front perspective view of a portable toilet, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the portable toilet shown in FIG. 1 in a disassembled and compacted configuration; and, FIG. 9 is a front perspective view of the portable toilet shown in FIG. 1 in an open configuration.

The broken lines in the drawings illustrate the portions of the portable toilet, which form no part of the claimed design.
